United States Patent Office

Des. 216,275
Patented Dec. 9, 1969

216,275

VACUUM CLEANER

Ralph A. W. Johanson, Armonk, N.Y., assignor to Consolidated Foods Corporation, Old Greenwich, Conn., a corporation of Maryland

Filed Aug. 30, 1968, Ser. No. 13,325

Term of patent 14 years

Int. Cl. D7—06

U.S. Cl. D49—14.3

Fig. 2

Fig. 3

FIG. 1 is a perspective view of a vacuum cleaner, showing my new design.

FIG. 2 is a side view thereof.

FIG. 3 is a top plan view thereof.

FIG. 4 is an end view thereof showing the right end of the cleaner as viewed in FIGS. 1, 2 and 3.

I claim:

The ornamental design of a vacuum cleaner, as shown and described.
